DESIGN FOR JEWELRY-BASES.

Specification forming part of Design No. 7,417, dated May 5, 1874; application filed April 18, 1874.
[Term of Patent 3½ years.]

B.

To all whom it may concern:

Be it known that I, SHUBAEL COTTLE, of the city, county, and State of New York, have invented a new and original Design for Jewelry-Bases, of which the following is a specification:

The figure is a view illustrating my design.

My invention has for its object to furnish, and consists in, a new design for the bases of buttons, studs, pins, ear-rings, scarf-pins, lockets, and other articles of jewelry, as hereinafter described.

A is the center, which is surmounted by, or is made solid with, a rim or bissel, B, which

is itself surrounded with a row of shot, C. The shot C are surrounded with a wide flat border, D. The central portion A is made square or oblong, and the border D is made circular or oval, as shown.

I claim as my invention—

The design for jewelry-bases, herein shown and described, formed by the wide flat border D about a row of shot, C, surrounding a rectangular central portion, A.

SHUBAEL COTTLE.
